TREATMENT OF HYDROCARBONS

Application filed July 22, 1927. Serial No. 207,793.

This invention relates particularly to improvements in the production of light petroleum distillates, such as kerosene, benzine, gasoline and light cracked distillates. The 5 invention includes improvements in the treatment of such light oils and also includes improvements in the treatment of crude petroleum oils from which such light oils are subsequently to be separated.

10 One of the general methods employed for some time past in refining light petroleum oils consists in subjecting them to treatment with sulphuric acid, then to an alkali treatment and finally to a so-called "doctor" treatment. Following treatment with sulphuric acid, the oils are frequently rerun, that is redistilled, and the alkali treatment may be combined with this redistillation, for example by carrying the distillation out over an 15 alkali or an alkaline substance. The doctor treatment is usually made the final step in the sequence of operations to insure a "sweet" product.

One of the purposes of the doctor treatment as it has been employed is the elimination 20 of objectionable sulphur compounds, including organic sulphides such as the mercaptans, and, in the case of oils that have been subjected to previous treatment with sulphuric acid, frequently sulphur-containing 25 compounds introduced as a result of the acid treatment or through decomposition of constituents introduced by acid treatment, such as the alkyl sulphates. Such sulphur-compounds are objectionable because they tend 30 to render the oil unstable on exposure to light, and to impart to it bad color and odor and corrosive properties.

In the doctor treatment, as usually carried 35 out, the oil is agitated or otherwise brought into intimate contact with the doctor solution and a so-called "break" is then effected by the addition of elementary sulphur. Due to difficulties of control, there usually remains 40 in the oil either soluble sulphur compounds produced by reaction with the doctor solution or, more frequently, elementary sulphur because of the necessity of employing an excess of sulphur to bring about the break.

45 When the break occurs, the reaction products

of the doctor treatment form flooky masses which carry down a large part of the objectionable constituents.

This invention provides an improved method of treating light petroleum oils which 55 minimizes difficulties such as those encountered in application of the so-called doctor treatment while at the same time effecting the purposes of such treatment, in many cases with an actual improvement in the results 60 secured. The invention has several important advantages which will appear as the description proceeds.

According to the present invention, the 65 petroleum oil is subjected to treatment with an alkaline aqueous solution comprising sodium hydroxide and copper oxide advantageously free from undissolved copper oxide. Solutions of this character exhibit properties particular with respect to their action 70 on petroleum oils which indicate the formation of sodium cuprate in the alkaline aqueous solution. This treatment may be carried out at ordinary temperatures simply by agitating the petroleum oil with the above noted 75 treating solution, in the manner in which such oils are customarily subjected to treatment with aqueous solutions of refining agents. The treatment is carried out with particular advantage, however, in connection with the 80 distillation or redistillation of the petroleum oil, particularly where the oil has previously been subjected to refining treatment with sulphuric acid. Where the treatment is carried out in conjunction with a distilling operation, the oil is heated in a still and vapors are driven off into a reflux tower, the vapors escaping from the reflux tower being condensed to form the distillate product, and 85 an alkaline aqueous solution of the heating agent is introduced into the reflux tower in direct contact with the vapors of the oil undergoing distillation. The treating solution is advantageously supplied to the reflux tower in the form of an emulsion with additional 90 fresh oil.

A treating solution suitable for use in carrying out the present invention may be made, for example, by saturating a 50° Bé. 95 aqueous caustic soda solution with black cop-

per oxide at a temperature approaching the boiling point of the solution, say at a temperature approaching 285° F., and subsequently diluting the solution to about 30° 5 Bé. before use. At elevated temperatures, a 50° Bé. caustic soda solution will absorb as much as 0.35 to 0.50% of black copper oxide. Before use, and advantageously after dilution, the solution is allowed to stand to permit 10 any undissolved material to settle.

In one way of carrying out the invention, in the treatment of raw kerosene or raw gasoline for example, the oil is first washed with say 1% or somewhat more of 15-30° 15 Bé. caustic soda solution to eliminate hydrogen sulphide and other easily removed sulphur and then, after separation of the caustic soda solution, is agitated, with air or mechanically, with from 3 to 5% of a treating 20 solution comprising sodium hydroxide and copperoxide, prepared as previously described, until the oil is doctor sweet. The use of such treating solutions free from undissolved copper oxide is particularly advantageous in 25 such operations. After agitation, the oil is separated from the treating solution and from any suspended impurities by settling. A quick clean break is uniformly secured, and this quick clean break is one of the important advantages of the invention. The 30 separated oil is then washed with water and may be subjected to a variety of subsequent treatments.

For example, the separated oil may be subjected to a light treatment with sulphuric acid, with say from 1 to 4 pounds of acid per barrel, and after separation of acid sludge agitated with from $\frac{1}{2}$ to 3 pounds per barrel of fine fuller's earth until all traces of acidity 40 are removed. The fuller's earth may then be separated from the oil in any convenient manner, for example by settling or by filtration.

As another example, the separated oil from 45 the treatment with the alkaline aqueous solution containing sodium hydroxide and copper oxide, after washing, may be contacted with dry cupric chloride, as described in an application filed May 29, 1926, Serial No. 50 112,638. Following the cupric chloride treatment, the oil may be subjected to a light treatment with sulphuric acid or it may be treated directly with fuller's earth, as also described in the application just referred to. 55 If the oil is treated with sulphuric acid following the cupric chloride treatment, it is advantageous to effect neutralization of any remaining acid by treatment with fine fuller's earth, as described above.

In another way of carrying out the invention, in the treatment of naphtha character fractions which have been subjected to refining treatment with sulphuric acid, the naphtha fraction is distilled in a still provided with a reflux tower, both of ordinary

construction, and a alkaline aqueous solution comprising sodium hydroxide and copper oxide is introduced into the reflux tower in direct contact with the vapors therein, for example as an emulsion with additional oil supplied to the distillation. The treating solution may be prepared as previously described or it may contain a somewhat greater proportion of copper oxide. The treating solution so supplied to the distilling operation, for example, may amount to from 1 to 4% of the oil supplied to the operation. The distillation may be carried out on a batch basis, or on a continuous basis, that is with supply of fresh oil and discharge of residue during the operation. 70 75 80

One form of apparatus, adapted for use in carrying out the invention in this way, is diagrammatically illustrated in the accompanying drawing. 85

The still 1 is of conventional construction. A charging line 2 is provided for initially charging the still and a draw off line 3 for the discharge of residual oil. Arranged above the still is a reflux or fractionating tower 4 provided with a continuous helical baffle to permit contact with heat exchange between liquid and vapor components within the tower without spraying liquids through the vapors or bubbling vapors through liquids. This type of tower is particularly useful in carrying out the invention but other types of towers may also be used. The vapors escape from the top of the tower through vapor line 5 to the condenser 6 where they are condensed to form the distillate product run off through the "look box" connection 7. To assist in control of the tower, a light fraction, such for example as a part of the distillate produce or a fraction of corresponding character, may be introduced through connection 8. Fresh oil is introduced near the upper end of the tower through connection 9 by means of centrifugal pump 10. Connection 11, including control valve 13, opens into the intake connection 12 of the pump 10. 90 95 100 105 110

In distillation of the oil being treated in the apparatus illustrated, the oil, or the lighter part of the oil, is vaporized in the still 1, the heavier components of the vapors are condensed in the tower 4 and refluxed to the still, and the vapors escaping from the tower 4 are condensed to form the distillate product in the condenser 6. 115

The treating solution is supplied through connection 11 and, in the pump, is emulsified with fresh oil flowing to the pump through connection 12 so that the treating solution enters the upper part of the tower 4 through connection 9 intimately mixed with fresh oil. In the tower, the treating solution is brought into intimate and effective contact with the vapors of the oil undergoing distillation and with the liquid condensate refluxed to the still. All of the oil is thus effectively sub- 120 125 130

jected to treatment with the treating solution, including the products of any decomposition taking place in the tower 4. The various reaction products, and any residue of the treating solution, are carried downwardly into the still with the unvaporized or condensed oil and are removed from the still, in continuous operation, largely in suspension in residual oil discharged from the still.

10 In carrying out the invention in this way, finished gasolines, for example, can be obtained directly as the distillate product without further treatment from naphtha fractions, from crude oils or cracked oils or mixtures of the two, which have been subjected to previous refining treatment with sulphuric acid in the usual way.

15 The invention is also useful in the direct treatment of crude petroleum oils from which light petroleum oils are to be separated. In carrying out the invention, in the treatment of crude petroleum oils, the vapors driven off from the crude oil during distillation, to separate light oils such as kerosene, benzine 20 and gasoline, are subjected to treatment with an alkaline aqueous solution comprising sodium hydroxide and copper oxide prepared as previously described.

25 The crude oil may be subjected to distillation in a still provided with a reflux tower, of the general type illustrated in the drawing and just described, and the treating solution introduced into the reflux tower as described in connection with the rerunning of naphtha 30 character fractions. The treating solution may be so supplied directly to the reflux tower on the crude still as such, or as an emulsion in the crude oil, or part of the crude oil, supplied to the operation, or as an emulsion 35 in a lighter oil, for example, in oil of the character of the distillate product. In carrying out the invention in this way, light petroleum oils which are doctor sweet just as they come from the still and which remain doctor 40 sweet can be obtained from many crudes.

45 We claim:

1. In refining petroleum oils, the improvement which comprises subjecting the oil to treatment with an alkaline aqueous solution 50 comprising sodium hydroxide and copper oxide free from undissolved copper oxide.

2. In refining petroleum oils, the improvement which comprises subjecting vapors of the oil to treatment with an alkaline aqueous 55 solution comprising sodium hydroxide and copper oxide free from undissolved copper oxide.

3. In refining petroleum oils, the improvement which comprises distilling the oil and 60 subjecting the vapors of the oil undergoing distillation to a refluxing operation in direct contact with an alkaline aqueous solution comprising sodium hydroxide and copper oxide free from undissolved copper oxide.

65 4. In refining petroleum oils, the improve-

ment which comprises distilling the oil and subjecting the vapors of the oil undergoing distillation to a refluxing operation in direct contact with an alkaline aqueous solution comprising sodium hydroxide and copper 70 oxide supplied to the refluxing operation as an emulsion with additional oil.

5. In the distillation of crude petroleum oils, the improvement which comprises subjecting the vapors of the crude oil undergoing 75 distillation to treatment with an alkaline aqueous solution comprising sodium hydroxide and copper oxide free from undissolved copper oxide.

6. In rerunning petroleum naphthas, the 80 improvement which comprises distilling the naphtha and subjecting the resulting vapors to a refluxing operation in direct contact with an alkaline aqueous solution comprising sodium hydroxide and copper oxide free from 85 undissolved copper oxide.

7. In rerunning petroleum naphthas, the improvement which comprises distilling the naphtha and subjecting the resulting vapors to a refluxing operation in direct contact 90 with an alkaline aqueous solution comprising sodium hydroxide and copper oxide supplied to the refluxing operation as an emulsion with additional naphtha.
